UNITED STATES PATENT OFFICE

168,158

CARRIER FOR FLATWARE

Edward Keating, Glenview, Ill., assignor to Ekco Products Company, Chicago, Ill., a corporation of Illinois

Application December 26, 1950, Serial No. 13,592

Term of patent 14 years

(Cl. D44—29)

To all whom it may concern:

Be it known that I, Edward Keating, a citizen of the United States, residing at Glenview, county of Cook, and State of Illinois, have invented a new, original, and ornamental Design for a Carrier for Flatware, of which the following is a specification, reference being had to the accompanying drawing, forming part thereof.

Fig. 1 is a top perspective view of a carrier for flatware embodying my new design.

Fig. 2 is an enlarged front elevational view thereof.

Fig. 3 is an enlarged side elevational view thereof.

I claim:

The ornamental design for a carrier for flatware, as shown.

EDWARD KEATING.
